CONSTANT TENSION SPEED-VARYING CONTROL FOR SPINNING FRAMES OR THE LIKE

George M. Heller and Paul B. Reeves, Columbus, Ind., assignors to Reeves Pulley Company, Columbus, Ind., a corporation of Indiana

Application October 6, 1948, Serial No. 53,164

17 Claims. (CL 57—98)

1

The present invention relates to control means interposed in the driving train for a spinning frame, or the like, and intended to improve the efficiency and speed of such a machine by maintaining optimum speed of the machine at all times. Optimum speed, of course, is the highest possible speed, at each given instant during the cycle of operation of the machine, which will permit continuous operation without an excessive number of "ends down" or breaks in the various strands being wound.

A given set of strands will, of course, withstand a predetermined degree of tension. It has been ascertained that the tension existing in the portion of each strand extending between the guiding eyelet on the thread board and the bobbin, varies in accordance with three primary factors; viz., the currently existing angle at which the strand meets the effective periphery of the bobbin, the lineal distance between the traveler and the effective surface of the bobbin, and the lineal distance between the guiding eyelet and the traveler; these factors being here listed in descending order of importance. Each of these factors varies continuously during the operation of a spinning frame. In some types of operations, all three factors vary oppositely a great number of times during a cycle of operation. In another type of operation, the last factor varies oppositely while the other two factors vary progressively in one direction only.

It has been determined that tension in the critical portion of the strand decreases as each of the above factors decreases, and increases as each of the above factors increases; and that variation in the mentioned angle has the greatest effect upon tension, variation in the distance between the guiding eyelet on the thread board and the corresponding traveler on the ring rail has the least effect upon tension, and variation in the distance between the traveler and the currents effective surface of the bobbin has an intermediate effect upon tension. It follows that, in order to maintain maximum feasible operating speed, the speed of operation of the machine should be reduced as the weighted algebraic sum of the three factors increases, and should be increased as the weighted algebraic sum of those factors decreases.

In a few spinning frames which have recently become available, the thread board reciprocates with the ring rail, thereby eliminating the lineal distance between the guiding eyelet and the traveler as a variable factor.

It is a primary object of the present invention, then, to provide means for controlling the speed at which a spinning frame or the like will be operated by a constant speed power source, in response to variations in those variable factors. According to the present invention, a speed controlling means which is highly sensitive to move-

2

ments of a control element, is associated with the ring rail of a spinning frame, or the like, the control element following the movements of the ring rail, and further being affected as the effective diameter of the bobbin is increased by the addition thereto of successive layers of the strand being wound. A further object of the invention is to provide an arrangement whereby the control mechanism may be made properly responsive to the movements of a spinning frame ring rail, whether that frame is being used to perform a filling wind, a warp wind, or a combination wind.

Further objects of the invention will appear as the description proceeds. To the accomplishment of the above and related objects, our invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is a perspective view of a fragment of a spinning frame of conventional construction having associated therewith a drive train including a speed-varying mechanism and control mechanism for actuating the speed-varying mechanism in response to changes in the defined dominating factors;

Fig. 2 is a fragmentary end elevation of portions of the drive train;

Fig. 3 is an enlarged fragmentary illustration of a fluid motor used in the organization of Fig. 1;

Fig. 4 is a perspective view of a control mechanism used in filling winding operations, and the panel upon which it is mounted;

Fig. 5 is a fragmentary perspective view of a portion of the control mechanism in a different position of adjustment;

Fig. 6 is an enlarged horizontal sectional view taken substantially on the line 6—6 of Fig. 5;

Fig. 7 is a fragmentary end elevation of parts of the control mechanism of Fig. 4;

Fig. 8 is a view similar to Fig. 4 but showing control mechanism used in performing a warp winding or combination winding cycle;

Fig. 9 is an enlarged fragmentary front elevation of details of the mechanism shown in Fig. 8;

Fig. 10 is a sectional view taken substantially on the line 10—10 of Fig. 9; and

Fig. 11 is an enlarged fragmentary front elevation of a detail of the mechanism illustrated in Fig. 8.

Referring to Fig. 1, it will be seen that we have illustrated an end fragment of a spinning frame 20 provided with a plurality of spindles or bobbins 21 with which is associated a ring rail 22 having a plurality of guide rings 23, each of which is provided, in accordance with standard practice, with a traveler 16. Strands drawn from

bobbins 25 are led through eyelets 24 on the standard thread board 15, thence through the travelers 16, and so to the spindles or bobbins 21 which are rotated at high speed by any suitable means. Conventional means is provided for reciprocating the ring rail 22 as the bobbins 21 are rotated, the entire mechanism being driven, in accordance with standard practice, from a main shaft 20'.

According to the present invention, a motor 27, mounted upon a suitable frame, carries on its spindle a resiliently expansible pulley 28, which pulley may comprise a coned disc 29 fixed to the motor spindle, a mating coned disc 30 splined thereon, and spring means, contained within a housing 31, continuously urging the disc 30 toward the disc 29. A belt 32 provides a driving connection between the expansible pulley 28 and a V pulley 33 rotatably fixed on, but axially slidably with respect to, a shaft 34 which is journalled in a frame 35 mounted for oscillation upon a journal element 26. Said journal element is supported upon a standard 14 which, in turn, is mounted upon an adjustably positionable base 13 whereby, through adjustment of said base, said element 26 may be brought into substantial coaxial relation with the main shaft 20' of the spinning frame with which the control assembly is associated. The shaft 34 carries, outboard with respect to the frame 35, a V pulley 17, which is connected by a belt 18, to drive a V pulley 19 conventionally fixed to the main shaft of the spinning frame. A fluid motor, indicated generally by the reference numeral 36, has a journalled supporting association with the free end of the frame 35 through trunnions 38' received in ears 35'.

The motor 36 comprises a cylinder 37 within which is reciprocably received a piston 38 having a stem or rod 39 projecting through one end of the cylinder 37 and pivotally supported, as at 40, upon a portion 41 of the base 13. Obviously, as fluid is supplied to one end or the other of the cylinder 37, said cylinder will be moved bodily, in the general direction of its axis, in one direction or the other with relation to the piston 38. Because of the rocking connection between said cylinder and the free end of the frame 35, the frame 35 will be correspondingly oscillated about the element 26, carrying with it the shaft 34 and pulleys 33 and 17. Since the axis of oscillation of the frame 35 is substantially coincident with the axis of the pulley 19 on the machine main shaft, such movement of the pulley 17 does not affect the belt connection between the pulleys 17 and 19. As the pulley 33 is moved away from the axis of the spindle of the motor 27, however, the belt 32 will be crowded more deeply between the discs 29 and 30, separating said discs against the tendency of said spring means in the housing 31, and reducing the effective diameter of the pulley which drives the belt 32 to reduce the speed at which the shaft 34 will be driven. Concurrently, the pulley 33 will drift axially toward the right, as viewed in Fig. 1, to maintain alignment of the belt 32. Correspondingly, as the shaft 34 is moved toward the axis of the spindle of the motor 27, the belt will be squeezed outwardly between the cones 29 and 30 by the action of the spring associated therewith, to increase the effective diameter of the pulley 28 and to increase the speed at which the shaft 34 will be driven; while the pulley 33 will move to the left on said shaft 34.

Pipes 42 and 43 lead from a control valve 44,

carried on the cylinder 37, to the opposite ends of said cylinder; and flexible conduits 45 and 46 lead, respectively, from a source of fluid under pressure to the valve 44, and from said valve to a reservoir or to waste. A control lever 47 controls the flow of fluid to and from the opposite ends of the cylinder 37 through the pipes 42 and 43. As the lever 47 is moved in a clockwise direction, as viewed in Fig. 1, fluid under pressure will be supplied to the lower end of the cylinder 37 and will be exhausted from the upper end of said cylinder, thereby swinging the frame 35 in a counterclockwise direction to reduce the speed at which the shaft 34 is driven. When the lever 47 is in its position illustrated in Fig. 1, fluid flow to and from the cylinder 37 will be arrested. When the lever 47 is moved in a counterclockwise direction from its position so illustrated, fluid will be supplied to the upper end of the cylinder and will be released from the lower end thereof, to move the frame 35 in a clockwise direction to increase the speed at which the shaft 34 is driven.

A control panel 48 (Fig. 4) is mounted adjacent the spinning frame 20, being carried either on said machine or on the supplemental base supporting the drive train; and preferably a closure cover 49 (Fig. 1) is normally associated therewith. A rod 50 is operatively associated, by means of a pair of collars 51 removably and adjustably mounted on its upper end, with a projection 52 from the ring rail 22; and at its lower end, said rod carries a block 53. The rod 50 reciprocably penetrates a second block 54 fixed to a slide 55 reciprocably mounted upon a guide 56 whose axis is parallel with that of the rod 50. Near its upper end, the rod 50 is guided in a block 57 fixed to the panel 48.

Fixed to the block 53 is a rigid strap 58 to the outer end of which is pivoted, as at 59, one end of a link 60. To the upper end of said link 60 is pivoted, as at 61, one end of a second link 62 which carries at its opposite end, a roller 63. Pivoted to the link 62 upon the axis of the roller 63 is one end of a lever 64 pivoted, intermediate its ends at 65, upon a projecting portion of the slide 55. The other arm 66 of the lever 64 is urged in a clockwise direction by a coiled spring 67 anchored at 68 upon the slide 55.

The link 62 rigidly carries, at that end upon which is supported the roller 63, an arm 69 to which is fixed a slotted guideway 70. Slidably penetrating the slot of the guideway 70 is a screw 71 engaged in one end of a link 72 whose opposite end is pivoted, at 73, to one arm 74 of a bell crank lever 75 mounted at 76 upon a projecting arm 77 of the panel 48. A stop 72' is adjustably secured in the guideway 70 near the lower end thereof to limit downward movement of said screw 71 relative to said guideway; and upward movement of said screw is limited by the block 69'. The other arm 78 of said lever 75 is pivotally associated, as at 79, with the lower end of an actuator rod 80. A coiled spring 81 has one end secured, at any one of a plurality of points in the length thereof, to the lever arm 78, its opposite end being suitably anchored to exert a clockwise force upon the lever 75. The upper end of the rod 80 is operatively connected to the lever 47, at any one of a plurality of points in the length of said lever; and a turn-buckle 82 is preferably interposed in the length of the rod 80 (see Fig. 1).

As is clearly illustrated in Fig. 6, the slide 55 comprises mating elements 83 and 84 snugly but slidably embracing the guide 56. The element 84 is provided with a neck 85 internally threaded for

adjustable reception of a plug 86 abutting one end of a coiled spring 87 received in said neck, the other end of said spring bearing against a friction shoe 88 which bears upon the guide 56 with a frictional effect dependent upon the adjustment of the plug 86. Thus, the slide 55 is frictionally restrained against movement upon the guide 56, so that it will retain any adjusted position against the effects of gravity and frictional forces exerted thereupon during the movement of the associated parts, but will respond to more positive forces exerted thereupon.

Cam means, indicated generally by the reference numeral 93, is mounted upon the panel 48 for cooperation with the roller 63, and, in the illustrated embodiment of the invention, provides a relatively sharply inclined region 90, a region 91 substantially parallel with the line of movement of the rod 50, and a further region 92 which is curved on a radius such that, in one position of the plate 86, the region 92 is centered on the pivot point 73. In the illustrated embodiment of the invention, such cam means comprises two separate plates, one of which 93, provides the surface 90 and is formed with a vertically elongated slot 94 penetrated by clamp means 95, whereby the position of the plate 93, and so of the surface 90, may be adjusted; and the other of which, 96, provides the surfaces 91 and 92 and is mounted upon the panel 48 through the medium of two slots 97 and 98, elongated upon lines substantially perpendicular to the rod 50 and penetrated by clamping means 99 and 100, respectively. It will be understood, of course, that this cam means herein illustrated is designed to correspond to tension conditions in a particular spinning frame; and that the particular design of the cam means used with any specific machine will depend upon the tension variation conditions found to exist in that specific machine.

A stop plate 101, having a forwardly projecting finger 102 disposed in the path of movement of the lever 72, is adjustably secured to the panel 48 by means of a vertically extending slot 103 in said plate and one or more clamping elements 104 penetrating said slot and engaging the panel 48.

Adjustably fixed to the rod 50 to move therewith is a block 105 which, under certain circumstances, engages the block 54 to shift the slide 55 downwardly in response to downward movement of said rod, as will appear more fully hereinafter.

In the operation of a spinning frame 28 to produce a filling type of wind or build upon the bobbins 21, the ring rail is caused to reciprocate through a path of constant length but of varying position. That is, the ring rail starts at the bottom of its stroke and moves upwardly through a predetermined distance and then returns to its original position. Customarily, on each fourth cycle, the upward movement of the ring rail is slightly elongated, whereafter its downward movement is of the previous extent, so that the bottom end of the path of the ring rail is located above the lower end of the path through which the ring rail moved upon its three previous reciprocations. Preferably, the block 105 will be so positioned on the rod 50, relative to the block 53, that the distance between said blocks will be substantially equal to said constant length increased by the height of the block 54, so that the block 105 will not strike the block 54 during the building cycle of the machine.

As has been stated, the rod 50 is freely reciprocable with respect to the block 54 which is fixed to the slide 55.

At the beginning of the cycle of the machine, when the ring rail 22 is at its lowermost position, the parts of the control of this invention will occupy positions substantially below those illustrated, the bottom end of the slide 55 being slightly above the position of the bolts 106, and the rod 50 being positioned to locate its attached block 53 closely adjacent the bottom end of said slide. In that position of the parts, the link 72 will be in contact with the projection 102 of the stop plate 101 and the screw 71 will be near the top of the guideway 70, depending upon the adjustment of said stop plate. The roller 63 will be pressed against the lower end of the cam surface 90 under the influence of the springs 67 and 81. The position of the bell crank lever 75 will, thus, be dependent upon the current position of adjustment of the stop plate 101, since the position of the finger 102 relative to the adjusted position of the slide 55 will determine the location of the screw 71 in the guideway 70. Dependent upon that relation, the screw 71 may be above or below the axis of the roller 63, or it may be coincident with said axis. The lever 47 will be in its neutral position, with the auxiliary frame 35 near the counterclockwise end of its stroke as viewed in Figs. 1 and 2, so that the speed ratio between the spindle of the motor 27 and the shaft 34 will be near its maximum and the spinning frame will be operated at or near its minimum speed.

Now, as the ring rail starts upwardly, the first reaction of the control will be to lift the block 53 and its attached strap 58 without affecting the position of the slide 55. Since the link 64 is connected to that end of the link 62 which carries the roller 63, and since the link 64 cannot move upwardly except upon corresponding movement of the slide 55, it will be clear that the above-described movement of the rod 50 will cause clockwise swinging movement of the link 62, as viewed in Fig. 4, about the axis of the pivotal connection between the links 62 and 64. Since the guideway 70 is fixed with respect to the link 62, the guideway 70 will likewise be swung in a clockwise direction about the pivotal axis between the links 62 and 64.

If the screw 71 is currently coincident with that axis, the lever 75 will not be affected by such upward movement of the rod 50. If the screw 71 is currently above that pivotal axis, the lever 75 will be moved in a clockwise direction by such swinging movement of the guideway 70; or if the screw 71 is currently below that axis, such upward movement of the rod 50 will result in counterclockwise movement of the lever 75.

Clockwise movement of the lever 75, of course, lifts the rod 80 to move the lever 47 in a counterclockwise direction, as viewed in Fig. 1, to admit fluid to the upper end of the cylinder 37 and release fluid from the lower end thereof, which, of course, results in clockwise movement of the frame 35 about its journal element 26, and an increase in the speed of the shaft 34; while counterclockwise movement of the lever 75 operates oppositely to decrease the speed of the shaft 34, and so of the spinning frame. It will be seen that movement of the cylinder 37 in response to either type of adjustment of the lever 47 carries with it the valve housing 44 and has the effect of returning the lever 47 to a neutral position.

As the rod 50 returns to its lowermost position, of course the guideway 70 is returned to its starting position, and concurrently the lever 75 is returned to its starting position, whereby the

frame 36 is returned to its starting position and the speed of the shaft 34 returns to its starting value.

As has been stated, the fourth cycle of reciprocation of the rod 58 lifts the block 53 to a new high position, which may be only a fraction of an inch above its previous high position. As said block attains its new position, it strikes the block 54 to lift the slide 55 slightly, thereby elevating the position of the link 64 and the position of the roller 63. Since the roller 63 is carried on the link 62 and is pressed against the cam surface 90 by forces applied by spring 67 through lever 64 and by spring 81 through lever 75, link 72, and guideway 70, such elevation of its position will cause it to move toward the right as viewed in Fig. 4, pivoting about the pin 65, and moving the link 60 slightly in a clockwise direction about its pivot point 59. The guideway 70 moves with the roller 63 to shift the lever 75 in a clockwise direction, thereby increasing the speed of the shaft 34 corresponding with the top of the path of the block 53. As the rod 58 again descends, the slide 55 will remain stationary in its new high position, so that the speed of the shaft 34 corresponding to the lowermost position of the block 53 will also be slightly higher than the previously corresponding value.

Operation of the machine continues in this same fashion, the slide 55 being elevated slightly each time the position of the path of reciprocation of the rod 58 is changed, and the roller 63 continually following the cam surface 90 until finally the roller moves off the cam surface 90 and onto the cam surface 91.

Depending upon the position of the adjustable stop 72', the parts will ultimately reach a condition in which the link 72 is always held above the stop finger 102.

It will be seen that this peculiar movement will cause the control elements to move continuously through a path of substantially constant length but of varying position. As the position of the path of reciprocation of the parts advances upwardly, the mean speed of the spinning frame will progressively increase, while still varying, during each reciprocating cycle, to compensate for variations in the factors determining tension in the strands being handled. The speed variation within each reciprocating cycle will be determined by the position or positions assumed by the screw 71 in the guideway 70 during the cycle.

It will, of course, be obvious that the shape or contour of the cam surface with which cooperates the roller 63 determines the mean speed of the controlled machine during any specific reciprocating cycle of the rod 58. It will further be obvious that the optimum cam contour for any given machine, operating with a given type of strands, may be formed upon a single cam element which may be non-adjustably mounted upon the panel 48. With the particular machine illustrated, and with the type of strands selected for this disclosure, the mean speed of the machine should increase relatively rapidly during the early parts of the build, during which the roller 63 is riding on the surface 90, should then increase more gradually for a further period, during which the roller 63 is riding on the surface 91, and should then continue to increase at a predetermined rate through the remainder of the machine cycle. As has been stated, the surface 92 is machined on a curvature of such radius that, when the plate 96 is in one position, the surface 92 will be centered upon the pivot point

73. Under those circumstances, of course, the mean speed of the machine will not vary as the roller 63 rides the surface 92, since movement of the roller along said surface will not shift the lever 75. In practice, with the particular machine and strands selected for this disclosure, however, the plate 96 is tilted somewhat in a clockwise direction, whereby the concentricity of the surface 92 with the point 73 is disturbed. 10 The degree of tilting of the plate 96, of course, will determine the rate at which the mean speed of the machine will increase as the roller rides the surface 92. It will be obvious that, if the plate 96 is tilted in a counterclockwise direction 15 as viewed in Fig. 4, the mean speed of the machine will be caused to be reduced as the roller 63 traverses the cam surface 92. We presently believe that adjustability of the plate 96, which produces such flexibility of the mean speed of the machine during the final phases of the machine cycle, will be desirable in order to compensate for differences in the operation of individual machines and for differences in the strands being handled by the machine.

25 The wind or build will have been completed when the ring rail reaches a position in which the upper end of its stroke carries the roller 63 substantially to the upper end of the cam surface 92; and at that point, the machine will be stopped 30 and the bobbins 21 will be doffed and replaced by a new set of empty bobbins. Now, by conventional manipulation of the controls of the spinning frame, the ring rail will be returned to its bottom, or starting, position; and as it moves 35 downwardly, its extension 52 will carry with it the rod 50. The block 105 engages the block 64 to carry the slide 55 back to its lowermost, or starting position; and the above described cycle will be repeated.

40 In Figs. 8 to 11, I have illustrated a modified form of control mechanism to be used in connection with a spinning frame being operated to produce a warp build. In that type of operation, the first reciprocating stroke of the ring rail moves from the bottom of the bobbin substantially to the top of the bobbin and returns to a level a fraction of an inch short of its original starting position. On its next reciprocation, the ring rail stops a fraction of an inch short of the 45 upper end of its first reciprocation, and so on; each subsequent stroke of the ring rail being slightly shorter than the preceding stroke, but being symmetrical with respect to the midpoint of its original stroke. Thus, the ring rail may be 50 said to travel in a path of constant position but continually varying length.

In that form of the invention illustrated in Figs. 8 to 11, a panel 120 takes the place of the panel 48 of the previously described form, the rod 50 being guided in blocks 168 and 169 fixed to said panel. Block 121 is fixed to, and travels with, the rod 50; and a second block 122 is likewise fixed to said rod at a lower point. Clamping screws 123 and 124 operatively engage the respective blocks 121 and 122 to secure to said blocks a cam plate 125, said screws passing through laterally elongated slots 127 and 128 in said plate 125 to provide for adjustment of said plate relative to the rod 50. The cam plate is 60 formed with a rectilinear cam surface 126 which retreats from the axis of the rod 50 as it extends 65 upwardly.

A lever 129 is pivotally mounted, near one end, as at 130, upon a block 131 extending laterally 70 from one edge of the panel 120. A bell crank lever

132 is pivotally mounted, as at 133, at a point intermediate the ends of the lever 129, one arm 134 of said bell crank lever being pivotally connected at 135 to the lower end of the rod 50 which, as is illustrated in Fig. 1, is operatively connected to shift the valve-controlling lever 47. A spring 136 has one end connected to the lever arm 134 and has its other end anchored upon an abutment 137 adjustably supported on the adjacent edge of the panel 120, said spring continuously urging counterclockwise movement of the lever 132 as seen in Fig. 8. The other arm 138 of the lever 132 carries a roller 139 which rides the cam edge 126 of the plate 125 under the influence of the spring 136.

The free end of the lever 129 pivotally engages the lower end of a strap 140 which terminates in a slotted guide 141. In the illustrated embodiment of the invention, the guide 141 is welded to the upper end of the strap 140; but it will be obvious that said guide could be an integral portion of said strap.

Brake means, indicated generally by the reference numeral 142, is associated with the guide 141. Such brake means comprises a pin 143 fixed to 25 the panel 120 and projecting forwardly therefrom with a spacer 144 mounted thereon and providing an abutment for a friction washer 145 bearing against the rear surface of the guide 141. A second friction washer 146, mounted on the pin 143, bears against the front surface of said guide under the influence of a spring 147 confined between said washer 145 and a washer 148 which is adjustably positioned upon the pin 143 and is backed by an adjusting nut 149 threaded on the end of the pin 143. It will be obvious that, by manipulation of the nut 149, the degree of force with which the spring 147 grips the guide 141 between the washers 145 and 146 may be adjusted to a nicety. It will also be seen that the spring 136 tends always to lift the strap 140 and its associated parts.

Clutch means, indicated generally by the reference numeral 150, is likewise associated with the guide 141 below the point of association therewith of the brake means 142. Said clutch means comprises a pin 151 penetrating the slot of the guide 141 and having a head 152 bearing against the rear face of a link 153. A friction washer 154 is sleeved on the pin 151 and is pressed against the forward face of the guide 141 under the influence of a coiled spring 155 confined between said washer and a washer 156 sleeved on the pin 151 and backed by an adjusting nut 157 threaded on the outer end of the pin 151. It will be obvious that the degree of frictional engagement between the clutch means 150 and the guide 141 may be nicely adjusted by manipulation of the nut 157.

The link 153 cooperates with a link 162 to provide a toggle mechanism for producing movement of the clutch means 150. One end of the link 162 is mounted upon a fixed pivot 161, while its other end is pivotally connected, as at 163, with that end of the link 153 remote from the pin 151. At its end adjacent the pin 151, the link 153 carries a post 158 to which is secured one end of a coiled spring 159, the opposite end of which is anchored upon a post 160 fixed to the panel 120. The spring 159 tends always to move the uppermost end of the link 153 downwardly, toward engagement with an adjustable stop carried by the panel 120. As is most clearly shown in Fig. 10, said stop comprises a pin 170 having a head 171 disposed in the path of the head 152 of the pin 151. Said pin 170 passes through a vertically 75 peripheries of the bobbins.

elongated slot 172 in the panel 120 and is clamped in adjusted position therein by means of a spacer sleeve 173 and a nut 174.

Fixed to the block 122 is a bumper plate 165 whose upper end is inclined upwardly and toward the rod 50. The position of the plate 165 is such that, as it is moved upwardly into registry with the roller 164, it will engage said roller to tend to straighten the toggle comprising the links 153 and 162.

In Figure 8, the parts are shown in the positions which they occupy when the ring rail 22 is at the bottom of its stroke, and which correspond with minimum machine speed. As the ring rail rises, the cam plate 125 moves upwardly therewith, and the roller 139, under the influence of the spring 136, follows the inclined cam surface 126, whereby the speed of the machine will be gradually increased in the manner hereinabove described. Before the ring rail reaches the top of its stroke, the bumper plate 165 will engage the roller 164 to straighten the toggle, thereby moving the clutch means 150 upwardly. The tension of the spring 165 is so adjusted with respect to the tension of the spring 147 that the upward movement of the clutch means 150 will carry with it the guide 141, the strap 140, and the left-hand end of the lever 129, the clutch being assisted, of course, by the tendency of the spring 136. Thus, the position of the pivot point 133 will be elevated, whereby the position of the cylinder 37 corresponding to any position of rotational adjustment of the lever 132 will be elevated.

As the ring rail descends, the bumper plate 165 leaves the roller 164 to permit the spring 159 to bend the toggle, returning the roller 164 into its illustrated position, where it is stopped by engagement of the pin head 152 with the post head 171. The relative effectiveness of the brake means 142 and the clutch means 150, and the effect of the spring 136, are such that the guide 141 is retained, by the brake means, against retrograde movement with the clutch means 150.

Preferably the parts will be so proportioned that each actuation of the toggle by the bumper plate 165 will shift the lever 129 by precisely the amount necessary to compensate for the reduction of the weighted algebraic sum of the factors determining tension in the strands being wound; but if absolute accuracy cannot be attained, the parts are so related that each actuation of the toggle will move the guide 141 a little farther than necessary. The block 122 is so proportioned and arranged that its path is intersected by the roller 167 carried on the lever 129; and therefore, if the lever 129 is over-adjusted by any individual actuation of the toggle, it will be returned to accurate position when the block 122 strikes said roller near the downward end of the return stroke of the rod 50.

It will be seen, thus, that the speed of operation of the spinning frame is progressively increased during each upward stroke of the ring rail, to compensate for the corresponding reduction in the lineal distance between the travelers 16 and the eyelets 24, and is progressively decreased during each descent of the ring rail to compensate for the increase in that lineal distance. However, the mean speed of the machine is continually increased to compensate for the progressive reduction in the lineal distance between the travelers 16 and the effective surfaces of the associated bobbins, and for the change in the angle at which the strands meet the effective

The build having been completed, the operator will doff the machine and will return the machine to starting position, whereby the ring rail will be returned to its lowermost position. The rod 58, of course, moves with the ring rail; and, as it moves downwardly, the block 122 will engage the roller 187 to return the lever 128, and its associated parts, against the tendency of the spring 188 and the brake 142, to its starting position.

While it is presently believed that, when a spinning frame of the type selected for illustration of the present invention is used to perform a warp build, a rectilinear cam surface like that illustrated at 126 is optimum, it will be understood that, under different conditions, a modified cam contour might be desirable. The cam contour selected for cooperation with the roller 188 will be designed to produce such changes in the speed of the controlled machine as to maintain maximum machine speeds consonant with current tension conditions throughout the cycle of the machine; and to that end it may be necessary under special conditions to have a surface like the surface 126 oppositely inclined, or curved, or irregular, depending upon tension factors determined for a particular machine.

We claim as our invention:

1. For use with a spinning frame or the like including a main shaft and an element driven from said main shaft through a vibratory path, means for controlling the speed at which said main shaft is driven by a constant speed power source, comprising stepless variable-speed transmission means interposed between said power source and said shaft, power means connected to adjust the output speed of said transmission means, a member shiftable oppositely from a neutral position to actuate said power means oppositely, and means operatively connecting said element to shift said member.

2. The speed-controlling means of claim 1 in which said power means is a fluid-pressure motor.

3. The speed-controlling means of claim 1 in which said last-named means comprises a cam, a cam follower, means connecting said cam follower with said member, and means operatively connecting said element to produce relative movement between said cam and said cam follower in response to movement of said element through said vibratory path.

4. For use with a spinning frame including a main shaft, a plurality of bobbins, and a ring rail driven from said shaft, said ring rail carrying a traveler for each of said bobbins, means for controlling the speed of operation of said shaft, and so of said bobbins, to maintain substantially constant tension in strands being wound on said bobbins, while said shaft is driven from a substantially constant-speed power source, comprising a variable-speed power transmission mechanism operatively connected to transmit power from such source to such shaft and including an element shiftable oppositely to vary oppositely the output speed of said transmission, a fluid-pressure motor connected to shift said element, a control element for said motor shiftable oppositely from a neutral position to cause opposite actuation of said motor, and control mechanism operatively connected between said ring rail and said control element and operable to vary the effect on said control element of a given degree of movement of said ring rail.

5. In combination, a source of substantially

constant-speed power, a variable-speed transmission including an input shaft driven from said source, an output shaft, and means shiftable oppositely to vary oppositely the speed ratio between said shafts, a fluid-pressure motor including an element movable oppositely and operatively connected to shift said shiftable means, a control element for said motor adjustable oppositely from a neutral position about an axis movable with said movable element to actuate said motor oppositely, whereby movement of said movable element in response to adjustment of said control element in either direction tends to restore said control element to neutral position, a lever operatively connected to said control element, a cam, a cam follower, means operatively connecting said cam follower to shift said lever, and vibratory means driven from said output shaft and acting to produce relative movement between said cam and cam follower.

6. In a device of the class described, a reciprocator, means for driving said reciprocator through a path of constant length but varying position, a guide paralleling said path, a slide mounted on said guide, friction means resisting movement of said slide relative to said guide, means moving with said reciprocator to limit movement thereof relative to said slide and operable to shift the position of said slide to correspond with changing positions of the path of said reciprocator, a linkage including a portion carried by said reciprocator and a portion carried by said slide and elements connecting said portions, whereby relative movement between said reciprocator and said slide produces changes in the relative positions of said connecting elements, a guideway carried by one of said connecting elements, pivot means slidably engaged in said guideway, lever means, a link connecting said pivot means with said lever means, and means connecting said lever means to actuate a control for said driving means in response to movements of said link.

7. The device of claim 6 including cam means located adjacent the path of said slide, a cam follower fixed with respect to said guideway, and spring means resiliently urging said cam follower into cooperative engagement with said cam means.

8. The device of claim 6 in which said linkage portion carried by said slide is a lever pivotally mounted on said slide and pivoted, at a point remote from its connection with said slide, to that one of said elements carrying said guideway, and including cam means located adjacent the path of said slide, a cam follower substantially coaxial with the pivotal connection between said lever and said element, and spring means acting on said lever to urge said cam follower resiliently into cooperative engagement with said cam means.

9. In a device of the class described, a rectilinear guide, a slide mounted on said guide, means resisting movement of said slide relative to said guide, a reciprocator mounted adjacent said guide for axial movement substantially parallel thereto through a path of constant length but of varying position, cooperating abutment means moving with said reciprocator and with said slide and limiting relative movement thereof whereby the position of said slide relative to said guide is changed in response to variations in the position of the path of said reciprocator, a link having one end pivoted upon an axis fixed

with respect to said reciprocator, a second link having one end pivoted to said first-named link at a point remote from the pivotal mounting of said first-named link, a lever pivotally mounted on said slide and pivotally connected, at a point remote from its mounting, with said second link at a point remote from the pivotal connection between said first and second links, cam means located adjacent the path of said slide, a cam follower substantially coaxial with the pivotal connection between said lever and said second link, spring means acting on said lever to urge said cam follower resiliently into cooperative engagement with said cam means, a guideway rigidly associated with said second link, pivot means slidably mounted in said guideway, lever means, a further link connecting said pivot means with said lever means, and means connecting said lever means to actuate a control in response to movements of said link.

10. The device of claim 9 in which said pivot means is reciprocable in said guideway in a direction generally transverse to the direction of length of said second link.

11. The device of claim 9 in which said guideway has a portion coincident with the axis of pivotal connection between said first-named lever and said second link.

12. The device of claim 9 in which said guideway intersects, and extends in opposite directions beyond, the axis of pivotal connection between said first-named lever and said second link.

13. In a device of the class described, a reciprocator, means for driving said reciprocator through a path of varying length but constant position, cam means mounted to move with said reciprocator, a first lever mounted on a pivot, a second lever pivotally mounted on said first lever at a point remote from said pivot, a cam follower supported on said second lever, spring means resiliently urging said cam follower into cooperative engagement with said cam means, said second lever being connected to actuate a control for said driving means, brake means associated with said first lever to hold the same in any selected position of adjustment, and actuating means for shifting said lever incrementally in one direction against the holding effect of said brake means, comprising a friction clutch operatively associated with said lever and toggle mechanism for reciprocating said clutch, said toggle mechanism including a link mounted on a fixed pivot adjacent the path of said reciprocator, a second link having one end operatively attached to said clutch, the other ends of said links being pivotally connected together, means resiliently resisting straightening of said toggle mechanism, and means moving with said reciprocator and engageable with said toggle mechanism to straighten the same against such resistance.

14. In a device of the class described, a reciprocator, means for driving said reciprocator through a vibratory path of varying length and constant position, cam means moving with said reciprocator, a first lever mounted to swing about a pivot, a second lever pivotally mounted on said first lever at a point remote from said pivot, a cam follower supported on said second lever, means resiliently urging said cam follower toward cooperative engagement with said cam means, means connecting said second lever to actuate a control for said driving means, and means actuated by said reciprocator for moving said first

lever incrementally in one direction about its pivot in response to repeated reciprocations of said reciprocator.

15. The device of claim 14 in which said last-named means comprises friction brake means operatively associated with said first lever and tending to hold the same against movement, friction clutch means operatively associated with said first lever, means actuated by said reciprocator upon each reciprocation thereof to shift said clutch means relative to said brake means to move said first lever through a predetermined arc in one direction, and means for returning said clutch means, after each such movement thereof, without correspondingly moving said first lever.

16. In a device of the class described, a reciprocator, means for driving said reciprocator through a vibratory path of varying length and

20 constant position, cam means moving with said reciprocator, a first lever mounted to swing about a pivot, an element connected to said lever, a second lever pivotally mounted on said first lever at a point remote from said pivot, a cam follower

25 supported on said second lever, means resiliently urging said cam follower toward cooperative engagement with said cam means, means connecting said second lever to actuate a control for said driving means, stationary friction brake means

30 engaging said element and resisting movement thereof in response to the tendency of said resilient means, clutch means frictionally engaging said element, means moving with said reciprocator and operative to move said clutch means

35 bodily relative to said brake means, and thereafter to release said clutch means, during each cycle of reciprocation of said reciprocator, and means operative, upon such release of said clutch means, to return the same to its initial position.

40 17. The device of claim 16 in which said element is provided with an elongated slot and in which said brake means comprises a stationary mounted pin projecting through said slot, a spring sleeved on said pin, a friction member

45 sleeved on said pin and bearing on said element, and a nut threaded on said pin and adjustable axially thereof, said spring being confined between said nut and said friction member, and in which said clutch means comprises a pin projecting through said slot, and having a head cooperating with one face of said element to limit movement of said pin axially in one direction relative to said element, a friction member

50 sleeved on said pin and cooperating with the opposite face of said element, a nut threaded on said pin and adjustable axially thereof, and a spring sleeved on said pin and confined between said nut and said friction member.
